UNITED STATES PATENT OFFICE.

FRANCIS LANE, OF BRIERLEY HILL, AND WILLIAM ARTHUR MACHIN, OF BIRMINGHAM, ENGLAND.

ELEVATOR SYSTEM AND APPARATUS IN CONNECTION THEREWITH.

Application filed March 19, 1926, Serial No. 98,052, and in Great Britain April 22, 1925.

This invention is for improvements in or relating to elevator or transport systems, and apparatus in connection therewith, and more particularly to a system for use in the construction of embankments, and particularly the embankments formed from the refuse from mines and the like.

According to the present invention we provide an elevator or transport system comprising a truck adapted to be moved along a track-way, a cylindrical cage mounted on such truck so as to rotate thereon with its axis transversely to its length of the truck, that is, at right angles to the track-way, means for supporting or carrying refuse or the like in or on the cage and means for positively rotating said cage on its truck at a predetermined position on the track-way for depositing the refuse or the like, consisting of a driving connection adapted to be automatically established between the cage and the track-way.

The cage may have refuse containers which project axially thereof from each extremity so as to protrude beyond the sides of the truck whereby the refuse is adapted to be deposited on each side of the track-way, and the rotation of the said cage may be effected by an annular flange upon itself rolling upon a stationary flange suitably situated on or about the track-way such as at or about its extremity. Alternatively the cage may be set in rotation by a chain or like device encircling and attached to the said cage and which has a freely hanging part adapted to be arrested during the movement of the truck at a predetermined position on the trackway.

In a modification of the present invention the cage may be adapted to accommodate a complete wagon or tub, for which purpose rail sections may be disposed in the cage parallel to its axis, and means incorporated for retaining the wagon or tub whilst in engagement therewith during the tipping operation.

In order that this invention may be clearly understood and readily carried into practice, reference may be had to the appended explanatory sheet of drawings, upon which:—

Figure 1 is an elevational view illustrating an elevator system constructed according to the present invention, and

Figure 2 is a plan view of the system shown in Fig. 1.

Figure 3 illustrates the system in end elevation.

Figures 4 and 5 illustrate in side and end elevation respectively a truck with modified cage tipping mechanism.

In a convenient embodiment of the present invention, rails *a* are set at an inclination either upon a small mound which it is desired to extend or upon a suitable sub or trestle supporting structure. *b* is the truck having four wheels engaging the rails *a* and four grooved rollers *c* adapted to engage circumferential flanges on a skeleton cage *d*. Protruding from each extremity of this cage *d* is a refuse container *e*. Annular shallow drum-like flanges *f* are provided upon the skeleton cage *d*. A stationary dividing hopper *g* (see particularly Figure 3) is mounted above the truck at its lowest position adapted to direct refuse along the chutes *g*¹ into the containers *e*. The truck is adapted to be elevated in known manner as for instance by a cable *h* attached to the truck passing over the pulley *h*¹ and then to a pulley *h*² and by way of pulley *h*³ from a suitable power source. Further a counter-balance weight *i* mounted on wheels operating on a small track *i*¹ may be utilized such as is described in our concurrent application No. 11,096 dated 29th April 1925. This counter-balance weight *i* is attached to the truck by a separate cable passing over the pulley *i*². Towards the upper extremity of the rails *a* a special section of rail *a*¹ is utilized having a side frame *a*² provided with an upper contact flange *a*³.

In operation the truck after having had its containers *e* filled with the refuse is hauled up the track-way *a* until the flanges *f* run upon the contact flange *a*³ thereby setting the cage in rotation, as for instance, through 180 degrees to invert the containers *e* and deposit the refuse down the bank *j*. As this bank *j* extends, the upper section of rail *a*¹ may be separated from the lower sections *a* by a suitable jack or screw device and new sections of rails interposed between *a* and *a*¹. In this manner the contact flange *a*³ always remains adjacent the top of the mound *j*.

In the modification illustrated in Figures 4 and 5, the lateral containers *e* are dispensed with and the skeleton cage *d* provided with rails *d*¹, and thereby adapted to receive a wagon or tub *k*. Upper rails *d*² are provided

adjacent the top of the wagon wheels to prevent the wagon or tub leaving its rails d^1 during the tipping operation. The said wagon or tub may be further secured by a small pivotal lever l at each extremity thereof. The truck b and rollers c for supporting the cage may be substantially the same as that utilized in connection with the preceding arrangement. The Figure 4 illustrates a modified method of tipping or rotating the cage. For this purpose a chain, cable or like device m is attached, as for instance, at the point m^1 to the cage and allowed to depend as at m^2 , this depending extremity having a hook m^3 or like member adapted to engage a suitably devised stop or catch a^4 on the rail a^1 so that during the movement of the truck along the said rail the cage is set in rotation thereby automatically tipping the refuse from the wagon or tub k between the rails.

With the present apparatus it will be seen that an operator or operators may be employed at the lower extremity of the rail for the filling or loading operation of the cage, the tipping operation being effected automatically at the top of the mound and thereby avoiding the necessity of any operator or operators at this point.

30 What we claim as our invention and desire to secure by Letters Patent is:—

1. In combination with a trackway, an elevator system comprising a wheel truck adapt-

ed to be moved along said trackway by its wheels supporting said truck on said trackway, a cage carried by said truck and having cylindrical elements, rollers on said truck in engagement with said cylindrical elements enabling said cage to be rotated about an axis disposed transversely of said truck and said trackway, a container protruding from each side of said cage so as to overhang said trackway, said cage together with said containers being adapted to be lifted as a unit from said truck resting loosely thereon, and adjustable means for positively rotating said cage on said truck upon the latter reaching a predetermined position on said trackway for depositing on either side thereof the contents of said containers, said means automatically establishing an operative connection between said cage and said trackway as the movement of said truck along said trackway is continued beyond said predetermined position.

2. The combination as specified in claim 1, in which said adjustable means for rotating said cage comprises a side frame mounted on a special section of said trackway and provided with a flange adapted to cooperate with an annular flange on said cage.

In witness whereof we have hereunto set our hands.

FRANCIS LANE.
WILLIAM ARTHUR MACHIN.
